ARTHUR DEANE MOLONY, OF LONDON, ENGLAND.

PUTTEE.

1,118,038.

Specification of Letters Patent. Patented Nov. 24, 1914.

Application filed June 6, 1914. Serial No. 843,593.

To all whom it may concern:

Be it known that I, ARTHUR DEANE MOLONY, a subject of the King of Great Britain and Ireland, and resident subject 5 to the direction of the British Army Council, have invented certain new and useful Improvements in Putties; and I do hereby declare the following to be a full, clear, and exact description of the same.

10 This invention relates to improvements in putties.

Hitherto all putties have been wove in the same material, or materials, uniformly throughout their entire length.

15 For the severest conditions of wear putties have necessarily always been wove hard, smooth and compact, to better resist thorns, rubbing from hard rocks or riding, brushing from nails and other metal protectors

20 on the boots of the wearer, and rot from tropical sun and moisture. Less severe conditions have permitted a mixture of softer material with harder material in the puttee, to give more comfort to the leg. Still less

25 trying conditions have permitted a third form, entirely of soft material and having a rough finished surface. The soft material gives and takes slightly to the muscular movements of the leg. The rough surface

30 gives some purchase on the leg, and a mutual purchase between the turns of the puttee where they overlap one another, so that there is less tendency for the puttee to work undone to the discomfort of the wearer,

35 after a few hours activity on his part, and it is not necessary to do up the puttee so tight. The third form is often preferred, even under conditions in which the putties get worn and torn very rapidly, the comfort

40 gained being considered worth the extra expense of continual replacing.

Resistance to wear is usually more particularly required at that portion of the puttee which surrounds the lower part only of 45 the leg below the knee, and the highest degree of comfort is required at the calf and other parts, but it will be seen that, in the known forms of putties resistance to hard wear where required is not combined with

50 comfort where required.

The present invention has for its objects, *inter alia* to add comfort to all forms of putties for hard wear, especially military, without diminishing their strength: and to 55 adapt putties, as neater, more efficient and comfortable articles of wear, to many new

uses, chiefly sporting, for which the gaiter or combination of Highland spat and stocking have been worn hitherto. To this end, the invention is characterized by a woven 60 puttee having the warp or longitudinal strands retained jointless and continuous throughout, and having the weft or transverse strands changed in one or more suitably located longitudinal sections of the 65 puttee, so that that portion of the puttee which surrounds the part of the leg where the chief wear is is wove with a strong or comparatively strong material or materials, and the rest of the puttee is wove with less 70 strong or more comfortable material or materials, due to change of weft, the density of the weft strands being proportioned to avoid any ridge or abrupt change in thickness or compactness at the points 75 of change of the weft.

Several modifications of putties constructed according to the present invention are illustrated diagrammatically and displayed or extended, in the accompanying drawings:—

In the drawings like reference letters where repeated indicate like parts. Full single lines represent cotton threads. Full double lines represent flax threads. Dotted 85 single lines represent wool threads. Dotted double lines represent worsted threads. Wavy dotted lines represent fancy wool. Dots represent teazled parts. The brackets Z, Y, X, V, at the top of the drawings indicate different sectional lengths of the 90 respective putties, hereinafter referred to.

Figure 1 represents the outer side or inner side of a smooth finished puttee having a change of weft at the ankle end Z. *a* is 95 the warp of say cotton of the puttee. The ankle end is wove with weft, *b*, of soft material, say worsted, and rough finished or teazled on both sides for the length of about one turn of the puttee. The rest of the 100 puttee is compact wove and smooth finished, and made with weft, *c*, of harder material, say flax, to meet severe wear from high thorny bush or hard riding, or a mixture of softer and harder materials for where 105 the wear is not so trying but evenly distributed over the whole of the puttee where exposed, from ankle to knee. The soft weft ankle end is intended to be covered up entirely from outside wear when worn, by 110 the succeeding turn of the smooth finished portion being wound on so as to cover it

completely. By the softness of the ankle end, chafing of the top of the boot against the ankle is lessened. By the rough finish of the ankle end, a purchase on the boot 5 or foot is obtained that lessens the chance of the puttee working undone. A minor advantage is that stains from dubbin or other preparation on the boot will not show through to the outside surface of the puttee.

10 Warmth at this portion sometimes needed in colder climates is also obtained.

Figs. 2 and 2^a represent, respectively the outer and inner sides, and Fig. 3 represents the outer or inner side, of modifications of 15 putties having a change of weft at the tape or knee end V, as well as the ankle end Z. The knee end is wove with weft, d, of soft material, say wool. This makes the puttee more comfortable where conditions of wear 20 are severe but do not extend right to the top of the puttee, as in a country with low thorny bushes, or ordinary undergrowth, or ordinary riding. The knee end of the puttee may be rough finished or 25 teazled on the inside only, Fig. 2^a, or on both sides, Fig. 3, according to the amount of wear to be met on the surface. The puttee thus has a purchase at both ends which still further lessens the chance of the 30 puttee working undone.

Figs. 4 and 4^a represent respectively, the outer and inner sides of a modification of puttee having the change of weft at the tape or knee end adapted to extend farther 25 over the calf part X. The knee end is rough finished or teazled on both sides, and the part X is rough finished or teazled on the inside only and extends over the large muscles of the calf. This construction gives 40 a gain in comfort to the calf, and further helps to prevent the puttee from working undone. The puttee besides resisting severe wear where it surrounds the lower part of the leg, is suitable for conditions where the 45 wear is slight on the calf.

Fig. 5 represents the outer or inner side of a modification of puttee corresponding to Figs. 4 and 4^a, but rough finished or teazled on both sides of the part X. This 50 is suitable for conditions where the wear is practically *nil* on the calf but severe below.

Fig. 6 represents the outer or inner side of a modification of puttee corresponding to Fig. 5, but having a wool weft e instead of 55 a flax weft, at the part Y, extending from the ankle end to the bottom of the large calf muscles.

Fig. 7 represents a similar view of a modification of puttee corresponding to Fig. 5, 60 but having a wool warp, f, throughout, instead of a cotton warp; and having a cotton weft, g, instead of a flax weft, at the part Y, extending from the ankle end to the bottom of the large calf muscles.

65 Fig. 8 represents a similar view of a

modification of puttee corresponding to Fig. 7, but having fancy wool, o, at the knee end similar to that of a stocking.

Fig. 9 represents a similar view of a modification of a puttee corresponding to Fig. 7, but having a flax weft, h, instead of a cotton weft, at the part Y, extending from the ankle end to the bottom of the large calf muscles.

The constructions represented in Figs. 6 75 to 9 are suitable for the conditions, for example for which the Highland spat or a short cotton band are used with a stocking, or for conditions for which a stocking plain with the boot, or trouser plain with 80 the boot, are not quite strong enough. Thus every form of puttee hitherto made is improved by the invention, either in comfort without material diminution of strength, or in strength without material diminution in 85 comfort. The variation of materials enables a special form of puttee to be devised for particular conditions of wear.

Although various forms of construction have been illustrated, it will be understood 90 that the invention is not limited thereto and further modifications may be made without departing from the spirit of the invention. The lengths of the different sections of the puttee are based on the physique of the 95 human leg below the knee, and their mutual proportions are important to get the best results. The puttee is preferably made four inches wide, and in standard lengths that already existing kinds of putties are ready-made.

The ankle end, Z, is preferably made about one-tenth of "x," "x" being the full length of the puttee measured in the square, i. e. minus the tag, m, at one end for securing the tape, p, and minus the amount folded over at the other end, for the hem, n.

In Figs. 2, 2^a and 3, the knee end, V, is made approximately one-half of three-sevenths of nine-tenths of "x."

In Figs. 4, and 4^a, the portion X to cover the large muscles of the calf, is made approximately equal to the knee end, V. The portion Y, between the ankle and the large muscles of the calf is made approximately 115 four-sevenths of nine-tenths of "x." About two inches extra is added to the knee end in weaving to form the tape tag, and about one quarter inch extra is added to the ankle end in weaving to form the hem. The density 120 of the strands of the different materials used should be proportioned so as to obtain an even thickness and compactness, (not excepting the teazled portions) throughout the whole length of the puttee, and so as to obtain even pressure on the leg throughout, and avoid any ridge or abrupt change in thickness or compactness at the points of 125 change of the weft, particularly between the sections X and Y.

Having now particularly described and ascertained the nature of my said invention and in what manner the same is to be performed, I declare that what I claim is:—

5 1. A woven puttee consisting of warp or longitudinal strands and of weft or transverse strands, the warp strands being jointless and continuous throughout, and the weft strands being different in suitably located longitudinal sections of the puttee, the weft strands of that portion of the puttee which surrounds the part of the leg where the chief wear falls being of comparatively strong material, and the weft strands of the 10 rest of the puttee being of less strong or more comfortable material, and the density of the weft strands in the respective sections being proportioned to avoid any ridge and abrupt change in thickness and compactness, where adjacent sections meet, substantially as described.

2. A woven puttee consisting of warp or longitudinal strands and of weft or transverse strands, the warp strands being jointless and continuous throughout, and the weft strands being different in suitably located longitudinal sections of the puttee, the weft strands of that portion of the puttee which surrounds the part of the leg where the chief wear falls being of comparatively strong material, and the weft strands of the rest of the puttee, namely an ankle end section approximately one-tenth of the full length of the puttee, being of soft material, and the density of the weft strands in the respective sections being proportioned to avoid any ridge and abrupt change in thickness and compactness, where adjacent sections meet, substantially as de- 35 scribed.

3. A woven puttee consisting of warp or longitudinal strands and of weft or transverse strands, the warp strands being jointless and continuous throughout, and the weft strands being different in suitably located longitudinal sections of the puttee, the weft strands of that portion of the puttee which surrounds the part of the leg where the chief wear falls being of comparatively strong material, and the weft strands of the rest of the puttee, namely an ankle end section approximately one-tenth of the full length of the puttee, and a knee end section approximately one-half of three-sevenths of 50 nine-tenths of the full length of the puttee, being of soft material, and the density of the weft strands in the respective sections being proportioned to avoid any ridge and abrupt change in thickness and compactness, where adjacent sections meet, substantially as described.

4. A woven puttee consisting of warp or longitudinal strands and of weft or transverse strands, the warp strands being jointless and continuous throughout, and the 65

weft strands being different in suitably located longitudinal sections of the puttee, the weft strands of that portion of the puttee which surrounds the part of the leg where the chief wear falls being of comparatively strong material, and the weft strands of the rest of the puttee, namely an ankle end section approximately one-tenth of the full length of the puttee, a knee end section approximately one-half of three-sevenths of 70 nine-tenths of the full length of the puttee, and a section to cover the large muscles of the calf approximately equal to the knee end section, being of soft material, and the density of the weft strands in the respective sections being proportioned to avoid any ridge and abrupt change in thickness and compactness, where adjacent sections meet, substantially as described.

5. A woven puttee consisting of warp or longitudinal strands and of weft or transverse strands, the warp strands being jointless and continuous throughout, and the weft strands being different in suitably located longitudinal sections of the puttee, the weft strands of an ankle end section approximately one-tenth of the full length of the puttee, being of soft material, and the weft strands of an adjoining section approximately four-sevenths of nine-tenths of 75 the full length of the puttee, being of smooth wear resisting and strong material, and the density of the strands in the respective sections being proportioned to avoid any ridge or abrupt change in thickness and compactness, where adjacent sections meet, substantially as described.

6. A woven puttee consisting of warp or longitudinal strands and of weft or transverse strands, the warp strands being jointless and continuous throughout, and the weft strands being different in suitably located longitudinal sections of the puttee, the weft strands of that portion of the puttee which surrounds the part of the leg where the chief wear falls being of comparatively strong material, and the weft strands of the rest of the puttee being of less strong or more comfortable material, and the density of the weft strands in the respective sections being proportioned to avoid any ridge and abrupt change in thickness and compactness, where adjacent sections meet, and the angle end being rough finished, substantially as de- 100 scribed.

7. A woven puttee consisting of warp or longitudinal strands and of weft or transverse strands, the warp strands being jointless and continuous throughout, and the weft strands being different in suitably located longitudinal sections of the puttee, the weft strands of that portion of the puttee which surrounds the part of the leg where the chief wear falls being of comparatively strong material, and the weft strands 105

of the rest of the puttee being of less strong and more comfortable material, and the density of the weft strands in the respective sections being proportioned to avoid any ridge and abrupt change in thickness and compactness, where adjacent sections meet, and the ankle and knee ends being rough finished, substantially as described.

8. A woven puttee consisting of warp or longitudinal strands of weft or transverse strands, the warp strands being jointless and continuous throughout, and the weft strands being different in suitably located longitudinal sections of the puttee, the weft strands of that portion of the puttee which surrounds the part of the leg where the

chief wear falls being of comparatively strong material, and the weft strands of the rest of the puttee being of less strong or more comfortable material, and the density of the weft strands in the respective sections being proportioned to avoid any ridge and abrupt change in thickness and compactness, where adjacent sections meet, and the ankle and knee ends and calf portion being rough finished, substantially as described.

In testimony whereof I affix my signature, in presence of two subscribing witnesses.
